UNITED STATES PATENT OFFICE

HARRY E. HOWLAND, OF ITHACA, NEW YORK, ASSIGNOR TO ITHACA GUN COMPANY, OF ITHACA, NEW YORK

SINGLE TRIGGER MECHANISM FOR DOUBLE BARRELED GUNS

Application filed June 18, 1928. Serial No. 286,398.

This invention has relation to single trigger fire mechanism for double barrel guns and has for its object the provision of certain novel constructional features pertaining particularly to the trigger and the means whereby the firing of one barrel of the gun automatically sets the barrel selecting mechanism, so that the second action of firing will fire the other barrel.

10 The present invention has in view as an important consideration the simplified construction and arrangement of its tripping mechanism associated with the trigger, whereby the trip carrier may be more easily 15 taken out and replaced while the parts of the firing mechanism are being repeatedly assembled and disassembled in the manufacture of the gun.

20 The invention has in view further the novel construction and arrangement of certain features of the safety mechanism whereby the latter is rendered more sure and effective in its operation and preventing firing of the gun at untimely periods, or 25 accidentally.

The present invention comprises further and incidental features, the nature and purpose of which will be made apparent in the detailed description to be hereafter given.

30 In the accompanying drawings which illustrate a preferred embodiment of the invention constituting the subject matter of this application.

Figures 1 and 2 are elevations taken from 35 opposite sides of the breech casing of a gun, showing parts broken away or omitted to better illustrate the interior mechanism;

Figure 3 is a side elevation, on an enlarged scale illustrating essential features of 40 the trigger, trip and safety mechanism;

Figure 4 is a plan view of the devices illustrated in Figure 3;

Figures 5, 6, and 7 are fragmentary transverse sectional views of the tripping devices 45 set to different positions respectively.

As will be clearly understood the type of double barrel gun to which the invention relates is that in which the barrels are breech loading and are opened at their loading ends by breaking them from the stock.

The drawings represent so much of the mechanism of this character of gun as is necessary for a clear understanding of the particular features comprising the present invention.

Referring now to the drawings, the numeral 10 designates a shot gun breech mechanism including an upper tang 23, and lower tang 20. The latter is provided with the usual opening through which the trigger 15 operates, the upper end of the trigger being in the form of a plate 16, the forward end of which is provided with two upstanding ears 16', which are pivotally mounted in a recess 17 formed in an upstanding block 18 mounted on the lower tang 20 and carrying the horizontal pivotal pin 19 upon which the trigger rocks.

The trigger plate 16 includes a tail portion 19 which projects upwardly and rearwardly above the tang 20 beyond the edge of the trigger opening and has projecting from one side a pin 21, constituting part of the safety mechanism of the gun.

The numeral 23' designates the usual hammer and sears 24, the pivoted sears co-acting therewith. There sears have the usual forward ends 24' urged upwardly by springs 25 for engagement with shoulders on the hammer to maintain the latter in a cocked position. The sears 24 extend rearwardly in the form of two arms having inwardly turned fingers or studs 25', which co-operate with the trip 27. This trip is of well known inverted T-shaped comprising a horizontally, and longitudinally pivoted block, comprising the upstanding finger or stud 26' and the laterally extending arms 27' which latter overlap the edges of the trigger opening through the lower tang 20.

It has been customary heretofore, in guns of the type under consideration to form the trigger plate 16 with a cove or recess within which the trip is located, and in which the trip is pivoted directly to the trigger, 95 while the latter is pivoted to upstanding ears carried by the lower tang.

According to the present invention, however, the trip is not directly pivoted to the trigger, but is seated in a transverse cove or 100

recess 30 formed in a separate horizontally extending bar 31, which, at its forward end is mounted on the pin 19, of the recessed block 18, the recessed portion of which 5 extends through the block, to receive the bar 31, and allow vertical movement of the latter on its pivot 19.

In its normal or inoperable position the trip stands with its laterally projecting ears 10 27 resting on the lower tang 21. To operate, in the selective firing of the barrels, the upstanding part of the trip is thrown to the position for tripping one or the other of the sears by the following described mechanism.

Arranged rearwardly of the tail of the trigger is a vertical plate 32, supported on the lower tang 20 and provided with a projecting arm 34 on which is pivoted a lever 20 35. The upper end of this lever engages spring 36 which rests on a pin 37 projecting laterally from the elongated and flattened stem 38 of the safety slide or button 39 and has its free end formed with a tooth 25 or projection 39' which engage with notches 39² in the underside of the tang 23, and coact with the spring to indicate right, left or safety positions. The spring 36 has an upturned lip 40 at its forward end, slotted 30 for the passage of a tenon 41 on the rear end of a bar 42, the latter being connected to the breaking mechanism, so that when the gun is broken for loading purposes, the spring 36 will be moved rearwardly 35 by the rearward longitudinal movement of the plate 42, and will operate the lever 35, and throw its lower end across the pin 21 projecting from the tail of the trigger thus locking the trigger against firing operation 40 of "pulling".

This locked position which as explained is secured through the rearward movement of the plate 42 and spring 36, and this movement is consequent upon the breaking of the 15 gun, and in locking cannot be effected by closing the barrels to a firing position. Before unlocking can be effected, the safety button must be moved forward to disengage the lever 35 from the pin 21. This movement restores the plate 42 to its normal 50 position.

Pivoted to the tail of the trigger is a cam 45 having a forward face terminating at its lower end in a forwardly projecting 55 shoulder 46. The rear portion of the upper surface of the cam, indicated at 47 provides a stop surface, having its forward edge of slightly less distance spaced from the pivot point of the cam, than its rear edge.

The cam operates against the pin 49 projecting from the inner side of the plate 32.

The upper edge of the supporting plate 32 is provided with an angularly extending flange 32', the forward edge of which is 55 spaced from the pin 49 a distance slightly

greater than the distance between the front and rear faces of the cam, so that the upper portion of the cam may operate between the two surfaces.

The lower rear edge of the cam is provided with a stud 50 which is connected to the flange 32' by a spring 51 which normally urges the cam upwardly and the upper edge forwardly, so that the cam will be in contact with the stop pin 49. The function of this cam and spring is to normally maintain the rear end of the trigger in an elevated position so that the pin 21 is normally maintained at a position above the lower end of the lever 35 when in a neutral position, so that this lever when moving to neutral position must depress the trigger. When the trigger is in the neutral position, and depressed the upper end of the trip is spaced below the undersurfaces of the overhanging portions of the sears.

When released from neutral position, the spring 51 elevates the rear end of the trigger and brings the trip in contact with the sears.

The selective movements of the trip are controlled by a spring 52, one end of which is fixedly attached to the plate 32, and the other end secured to the upper part of the trip 27. It is to be understood that the main object and function of the cam 45 is to prevent doubling or premature firing of the second barrel after discharge of the first. When the first barrel is fired and the trigger drops down, the recoil forces the top of the cam rearwardly and under the projection 32' on the supporting plate 32 which blocks the trigger for an instant before the trigger drops down to move the trip over under the other sears.

The operation of the described mechanism is as follows:

Assuming the gun to have been loaded, cocked and placed in safe position, the trip will be centrally located below the sears as shown in Fig. 5. The spring 52 is of such construction that it tends to swing the upstanding link 26² of the trip beneath one of the sears, in the present instance beneath the left hand sear to the position shown in Fig. 6, but such movement is prevented by the lower end of the lever 35, which also prevents the pulling of the trigger. If now the slide or button 39 is moved to a position indicating firing of the left barrel, the spring 52 will throw the trip to the position shown in Fig. 6, which will cause to elevate the left hand member of the sear and thus ensure the firing of the left hand barrel.

If however the second or right hand barrel is to be fired, the safety button 39 will be moved to its second position, causing the lever 35 to press the spring 52 sidewise and throwing the trip to the right, in which position it will, when the trigger is operated,

ensure the selective firing of the right hand barrel. To provide for the movement of spring 52 the forward edge of the plate 32 may be notched as indicated by the number 53.

As before described, the present invention comprises the element 31, which is pivotally mounted on the pin 19 upon which the trigger is also mounted. The element 31 has therefore a small amount of motion independently of the trigger and is more sensitive in its actions.

In order to readily displace the trigger and the element 31, it is only necessary to take out the pin 19, to allow of the removal of the trigger and associated device.

This facility of disassembling and reassembling the parts is very advantageous in view of the necessity of frequently removing and replacing the parts in the manufacture of the gun, and in view of the desirability of having easily accessible and removable parts where interior changes or adjustments are required to meet the requirements or desires of the users.

What I claim as new is:—

In a single trigger mechanism for double barrel guns, the combination with a trigger operating through the usual trigger opening, a stationary block to which said trigger is pivoted, a bar having a width to pass through said opening and being pivotally and independently mounted on the trigger pivot, said bar being formed with a transverse recess, a trip pivoted to said bar within said recess and having a lateral length to bridge the trigger opening, means for selectively adjusting said trip, a pair of sears operatively connected to the firing mechanism, and means for selectively effecting the operation of the sears through the pulling of the trigger.

In testimony whereof I affix my signature.
HARRY E. HOWLAND.
